TRACK ASSEMBLY

Eldon D. Oestmann, Washington, Ronald L. Krolak,
Metamora, George F. Alexander, Pekin, and James T.
Duke, Peoria, Ill., assignors to Caterpillar Tractor Co.,
Peoria, Ill.

Filed Aug. 23, 1972, Ser. No. 283,066

Term of patent 14 years

Int. Cl. D15—04

U.S. Cl. D40—5

5-15-2.

FIG .3.

FIG. 1 is a side elevational view of a track assembly embodying our new design with the opposite side being a mirror image thereof.

FIG. 2 is a front elevational view thereof.

FIG. 3 is a rear elevational view thereof.

FIG. 4 is a top plan view thereof.

FIG. 5 is a side elevational view of a track assembly showing a second embodiment of our new design with the opposite side being a mirror image thereof and the front, rear and top plan views being identical to FIGS. 2, 3 and 4 respectively.

The broken lines are for illustrative purposes only.

We claim:

The ornamental design for a track assembly, substantially as shown and described.
